US00D856428S

(12) **United States Design Patent** (10) **Patent No.:** **US D856,428 S**
(45) **Date of Patent:** **** Aug. 13, 2019**

(54) **DIGITAL SIGN**

(71) Applicant: **LG ELECTRONICS INC.**, Seoul
(KR)

(72) Inventors: **Jungyeon Hwang**, Seoul (KR); **Yongho Lee**, Seoul (KR)

(73) Assignee: **LG Electronics Inc.**, Seoul (KR)

(**) Term: **15 Years**

(21) Appl. No.: **35/505,008**

(22) Filed: **Dec. 1, 2017**

(80) **Hague Agreement Data**

Int. Filing Date: **Dec. 1, 2017**

Int. Reg. No.: **DM/098937**

Int. Reg. Date: **Dec. 1, 2017**

Int. Reg. Pub. Date: **Jun. 1, 2018**

(30) **Foreign Application Priority Data**

Jun. 2, 2017 (KR) 30-2017-0025176

(51) **LOC (12) Cl.** **20-03**

(52) **U.S. Cl.**

USPC **D20/10; D20/42**

(58) **Field of Classification Search**

USPC D20/10, 19, 21, 42, 99; D14/127, 373;

D26/81, 93, 95

CPC G09F 7/00; G09F 13/04; G09F 19/02

See application file for complete search history.
